UNITED STATES PATENT OFFICE.

JOSEPH JEANNETAUD, OF DUBUQUE, IOWA.

ELECTRIC CLOTHES-PRESSE.

1,271,577.

Specification of Letters Patent.

Patented July 9, 1918.

Application filed August 6, 1915. Serial No. 44,063.

To all whom it may concern:

Be it known that I, JOSEPH JEANNETAUD, a citizen of the United States, residing at Dubuque, in the county of Dubuque and State of Iowa, have invented certain new and useful Improvements in Electric Clothes-Pressers, of which the following is a specification.

My invention relates to devices for use by tailors and those engaged in repairing clothes, with special reference to creasing pants, pressing collars and other kinds of care for clothes. And the leading object is to provide means whereby the wearer may crease his own clothes and that while he is wearing them, and without the aid of a tailor or other expert.

Another object is to dry and smooth out and press clothes including handkerchiefs and the like.

The manner of construction and mode of operation will be fully described in the following specification and illustrated in the drawings accompanying the same and forming a part hereof.

Figure 1 is a side elevation.

Fig. 2 is an end elevation.

Fig. 3 is a sectional view taken on line 3-3 of Fig. 2.

Fig. 4 is a sectional view taken on line 4-4 of Fig. 1.

Fig. 5 is a longitudinal sectional view of one of the ironing rollers.

Similar characters of reference denote similar parts in each of the drawings.

Having reference to the drawings 2 designates a frame, which is rectangular and consists of two sides 3 an end 7 and is preferably cast integral. In one side of the frame are secured two brackets 4 and in the other side are attached brackets 5. In the brackets 4 is journaled a roller 6 and in the brackets 5 is journaled another similar roller 8.

In each of the brackets 4 are set coil springs 10 that rest on and engage the journals of the roller 6 whereby the roller 6 is yieldingly mounted in the brackets and may be moved from or toward the roller 8 to adapt it to allow cloth of different thickness to 50 pass between the rollers.

The rollers are set in the brackets in such a manner that one side of the rollers are outside of the horizontal plane of the outer surface of the frame and the other side of the 55 rollers are inside of the plane of the surface

on the opposite side of the frame whereby the device may be used to operate on a flat surface.

Fastened by screws to the end 7 of the frame is a hollow handle 17, the opening in which registers with a corresponding opening in the frames. On the inside of the frame at each side is placed a plate or bracket 15 of non-conducting material to each of which is secured one of the electric wires 18 and also to these same plates are attached brushes 20 that rest upon and engage the collector rings 22 of the rollers 6 and 8. These electric wires pass up through an opening in the top or end piece 7 of the frame and through the handle 17 and connect with the electric supply. There is also encircling the collector rings 22^a of the rollers a brush 25 that forms an electric connection between the rollers.

75

The manner of operating my device is substantially as follows: The wires 18 are connected to an electric supply and the current passes down onto each of the collector rings of the rollers through the plate 15 and 80 through the brushes 20 and from one roller to the other through the brush 25. This heats the rollers 6 and 8 and then when they are sufficiently heated, the operator passes the parts of the trousers he desires to crease 85 between the rollers and runs the device up and down with the two parts of the pants between the rollers and this gives a crease as these rollers are hot with an ironing surface. If he desires to press or iron a collar 90 he also runs it between the rollers in the same manner. If he desires to press or iron any flat surface he turns the device on the side where the rollers are a little more than flush with the plane of the surface of one 95 side of the frame and runs it back and forward on the cloth to be pressed or dried the same as a sad iron.

It will be seen that it may be used for a large number of purposes without change 100 in construction and the springs will adapt the rollers to take between them, cloth or goods of different thicknesses.

Having now described my invention what I claim is:

105

In apparatus of the character described, a rigid U-shaped frame having spaced sides; a pair of rollers arranged within the frame and connected with the spaced sides thereof to move toward and away from each other; 110

yielding means to move the rollers toward each other; electrical heating elements arranged within the rollers; a spring element having electrical connection with corresponding ends of the heating elements and also serving to move the rollers toward each other; contacts carried by the sides of the frame and having permanent electrical connection with the opposite ends of the elec-

trical heating elements; and lead wires connected with the contacts.

In testimony whereof I affix my signature in presence of two witnesses.

JOSEPH JEANNETAUD.
